DRESS WITH LINGERIE CLAMP

Ruth Shapiro and Shirley B. Huber, Miami Beach, Fla.

Application March 30, 1954, Serial No. 419,662.

3 Claims. (Cl. 2-74)

This invention relates to a clamp or clip, and more particularly to a clamp for holding an article of clothing, such as a brassiere, in place.

The object of the invention is to provide a clamp which is adapted to be secured, as by sewing, to the inside of a woman's dress whereby a brassiere will not protrude out above the dress.

Another object of the invention is to provide a clip or clamp which is adapted to be sewed or affixed to the inside of a dress at or near the neck or breast line of the dress whereby the clip can be arranged in engagement with the top of a brassiere so that the dress and brassiere will cling together so that the brassiere will not accidentally pop out above the dress.

A still further object of the invention is to provide a clip which is especially adapted to be used with strapless and backless dresses or any type of low bosomed dresses whereby a brassiere or other article of lingerie will not accidentally protrude above the breast or neck line of the dress.

A still further object of the invention is to provide a lingerie clamp which is comfortable to use or wear, and wherein the device can be made of any suitable material, such as covered or uncovered resilient wire, plastic or other resilient material, solid spring metal which may be covered or uncovered, or any other springy substance.

A further object of the invention is to provide a lingerie clamp or clip which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a front elevational view of the lingerie clip, constructed according to the present invention.

Figure 2 is a rear elevational view of the lingerie clip, some of the parts being shown in section.

Figure 3 is a side elevational view of the clip.

Figure 4 is a fragmentary view taken through a woman's dress and brassiere showing the clip of the present invention in use.

Figure 5 is a front elevational view of a modified lingerie clip.

Figure 6 is a rear elevational view of the modified clip of Figure 5.

Figure 7 is a side elevational view of the clip of Figures 5 and 6.

Figure 8 is a front elevational view of another modified lingerie clip.

Figure 9 is a side elevational view of the clip of Figure 8.

Referring in detail to Figures 1 through 4 of the drawing, the numeral 10 designates a portion of a woman's dress, blouse or other article of clothing, and the dress 10 includes a body portion 11 that is provided with a neck opening 12 adjacent its top, and the opening 12 defines a neck or breast line 14, Figure 4. The numeral

2

15 designates a portion of a conventional brassiere which is arranged contiguous to the inner surface of the dress or other article of clothing 10, and the present invention is directed to a clip or clamp which is indicated generally by the numeral 16.

The clip 16 may be fabricated of any suitable bendable material, such as wire, and the bendable wire is indicated by the numeral 13 in Figure 2. A suitable covering 9 of fabric or other soft material may be arranged 10 on the outside of the wire 13.

The clip 16 is shaped to include a pair of side by side legs 17, each of which have their lower end terminating in a curved section 18 that defines an apertured ear, the aperture or opening being indicated by the numeral 19, Figures 1 and 2.

The clip 16 is adapted to be secured to the inner surface of the dress in any suitable manner as, for example, by means of threads 20, 21 and 22. The threads 20 may extend through the openings 19 and into engagement with the body portion 11 of the dress 10 while the threads 21 embrace or extend around the legs 17 and into engagement with the dress. It will be noted that the ears 18 are arranged angularly with respect to the legs 17 and this angular arrangement results from 25 constructing the clip out of a single piece of material. Extending downwardly from each of the ears 18 is a curved portion 23, and each of the curved portions 23 terminates in a curved finger 24. Each finger 24 is shaped to include an opening 25, and the threads 22 30 extend through the openings 25 and into engagement with the dress for maintaining the clip 16 secured to the dress or other article of clothing.

Extending from the top of each of the legs 17 is a curved web 26, Figure 4, and each of the webs 26 terminates in a downwardly extending arm 27. The arms 27 are arranged in superposed relation with respect to each other and the arms 27 are spaced from the legs 17 to define a space for receiving therein a portion of the brassiere 15, Figure 4. Thus, it will be seen that the webs 35 26 abut a portion of the top of the brassiere 15 whereby the brassiere 15 will be prevented from riding up or popping up accidentally above the neck line 14, Figure 4, since the webs 26 are abutted or engaged by the top edge of the brassiere. The lower ends of the arms 27 40 are interconnected together by a curved lip 28, and it will be seen from Figures 3 and 4 of the drawing that the lip 28 is spaced from the legs 17 a greater distance than the arms 27 so that a flaring or guiding mouth is 45 provided to facilitate the insertion of the brassiere 15 into the space between the arms and legs of the clip.

Referring to Figures 5, 6 and 7 of the drawing, there is shown a modified lingerie clamp or clip which may be made of the same material as the clip 16 shown in Figures 1 through 4. The modified clip of Figures 5 through 55 7 is indicated generally by the numeral 29 and includes a pair of side by side parallel legs 30, each of which have their lower end bent to provide a curved finger 31. The fingers 31 are provided with central openings 32. Threads or the like may be extended through the openings 32 and 60 around the legs 30 in order to secure the clip to a dress 10 in the same manner as shown in Figure 4.

Extending from the upper end of each of the legs 30 is a curved web 33, and each of the webs 33 terminates in a downwardly extending arm 34. The arms 34 are 65 spaced from the legs 30 whereby a portion of a brassiere, such as the brassiere 15, may be received in this space. The upper edge of the brassiere is adapted to engage or abut the webs 33 so that the brassiere will be prevented from protruding or popping out above the dress or neck line of the wearer. The lower ends of the arms 34 are 70 interconnected together by a curved lip 35 and the lip 35 is spaced from the legs 30 a greater distance than

the arms 34 in order to provide a flaring or guiding mouth for facilitating the placement of the brassiere within the space between the arms and legs of the clip.

Referring to Figures 8 and 9 of the drawing, there is shown another modified clip which is indicated generally by the numeral 36. The clip 36 can be made of any suitable material having the required degree of resiliency or rigidity and the clip 36 includes a straight portion defining a leg 37. The leg 37 is adapted to be secured to the inner surface of the dress or article of clothing in any suitable manner as, for example, by threads or sewing. Extending from the upper end of the leg 37 is a curved web 38 which is adapted to be engaged by the top edge of the brassiere being held in place, and projecting downwardly from the curved web 38 is an arm 39. The arm 39 may include an inwardly bowed intermediate portion 40, Figure 9, whereby slight clamping action will be effected on the brassiere to thereby retain a portion of the brassiere between the arm and the leg of the clip. The lower end portion 41 of the arm 39 flares outwardly to define a lip or mouth for guiding the brassiere into the space between the arm and leg when the brassiere is being initially placed therein.

From the foregoing, it is apparent that there has been provided a lingerie clip or clamp which will hold a brassiere 15 in place whereby the brassiere will not accidentally protrude above the neck or breast line of the wearer's dress so that the brassiere will not show on the outside. Although the clip has been specifically illustrated for use with a dress and brassiere, it is to be understood that it can be used with any two articles of clothing such as, for example, a blouse and slip.

In using the clip shown in Figures 1 through 4, the device is secured in place in any suitable manner as, for example, by means of threads 20, 21 and 22, and then the brassiere 15 is received between the arms and legs. Thus, the brassiere 15 will be prevented from moving up accidentally above the neck or breast line 15. If desired, the clip 29 shown in Figures 5 through 7 can be used in lieu of the clip 16 and the legs 30 and curved sections 31 can be secured to the inner surface of the dress by threads or the like. Again the brassiere is adapted to be received in the space between the arms 34 and legs 30. The modification shown in Figures 8 and 9, and indicated by the numeral 36, represents another lingerie clip wherein the leg 37 can be secured to the inner surface of the dress whereby a brassiere can be inserted or positioned between the arm 39 and leg 37 in order to prevent the brassiere from accidentally popping up above the neck line.

With the present invention, the dress 10 will cling to the brassiere 15 or the brassiere 15 will cling to the dress 10 so that the brassiere 15 will be prevented from popping out above the dress. This device is especially useful when women are wearing strapless or backless dresses but can also be used with all types of low bosomed dresses. The device is comfortable to wear and inexpensive to manufacture. The device can be made of covered or uncovered resilient wire, such as the wire 13, or can be made of other springy material.

What is claimed is:

1. In combination, a dress including a body portion having an opening defining a neck line adjacent its upper end, a brassiere arranged contiguous to the inner surface of said dress, a U-shaped clip, said clip being positioned with the legs thereof pointing toward the bottom of said dress, one of said legs being secured to the inner surface of said dress near the neck line thereof with the top of said U positioned below the neck line and the top of said brassiere being positioned within the space formed by said legs so that said brassiere is prevented from protruding above the said neck line.

2. The combination recited in claim 1 in which the other one of said legs of said U-shaped clip is formed with a curved lip at its lower end, said curved lip extending outwardly away from the leg of said U-shaped clip which is secured to the inner surface of said dress to thereby provide a flaring mouth at the lower end of said U-shaped clip.

3. The combination recited in claim 1 in which the leg of said U-shaped clip which is secured to the inner surface of said dress is provided with angular ears, said ears extending upwardly away from said last named leg of said U-shaped clip toward the other leg of said U-shaped clip, said angular ears being positioned intermediate the length of said clip.
